(74) Attorney, Agent, or Firm — John D.

Veldhuis-Kroeze; Westman, Champlin & Koehler, P.A.

(57) **CLAIM**

The ornamental design for an excavator, as shown and described.

DESCRIPTION

FIG. 1 is a perspective view of the excavator showing our new design;

FIG. 2 is a right side view thereof;

FIG. 3 is a left side view thereof;

FIG. 4 is a front view thereof;

FIG. 5 is a back view of thereof; and,

FIG. 6 is a top view thereof.

The broken lines shown in the drawings are included for purposes of illustrating portions of the excavator and form no part of the claimed design.

1 Claim, 6 Drawing Sheets(56)
